UNITED STATES PATENT OFFICE

2,263,384

FABRIC COVERED RING

Emil Grimaldi, Brooklyn, N. Y.

Application May 31, 1940, Serial No. 338,069

1 Claim. (Cl. 135—37)

This invention relates to fabric covered rings of the type disclosed in my Patent No. 1,514,962, issued November 11, 1924.

One object of the present invention is to provide such a ring having improved means for reinforcing the same to prevent opening up of the ring under strains to which it may be subjected.

The ring shown in my patent above referred to was not commercially practical because it opened up when subjected to a strain. In that ring, its characteristic feature was that it was fabric covered. In manufacture on an inexpensive quantity production basis, this necessitated that a plurality of yarns or threads be wound around a straight piece of wire in superimposed relation to each other. That piece of wire, thus covered, was then cut into sections and the latter bent into the ring form. Reinforcement of the ring at its split appeared to offer a great difficulty because it was necessary to avoid mutilation or destruction of the fabric covering. Another difficulty was the necessity for somehow anchoring the ends of the wound thread to prevent unraveling thereof.

It is therefore an object of the invention to provide a fabric covered ring of improved construction such that it shall avoid the difficulties mentioned and effect the advantages herein desired. A related object is to provide an improved ornamental ring-shaped article.

Other objects and advantages of the invention will become apparent as the specification proceeds.

With the aforesaid objects in view, the invention consists in the novel combinations and arrangements of parts hereinafter described in their preferred embodiments, pointed out in the subjoined claim, and illustrated in the annexed drawing, wherein like parts are designated by the same reference characters throughout the several views.

In the drawing:

Figure 1 is a plan view of the fabric covered ring embodying the invention.

Fig. 2 is a plan view showing the opposite side thereof.

Fig. 3 is an enlarged sectional view taken on lines 3—3 of Fig. 2.

Fig. 4 is a plan view of a section of the ring prior to its completion.

Fig. 5 is an enlarged side view of a die with the ring section of Fig. 4 placed in a horizontal plane thereon over a strip of metal, said ring section being partly broken away and a portion thereof being in section.

Fig. 6 is a similar view showing the ring only in section and illustrating a die in position for bending and clamping the metal strip to form an anchorage tube for the ring, after the concaving of said strip by the die of Fig. 5.

Fig. 7 is a similar view showing a modified strip member having an ornament accommodated by the die.

The advantages of the invention as here outlined are best realized when all of its features and instrumentalities are combined in one and the same structure, but, useful devices may be produced embodying less than the whole.

It will be obvious to those skilled in the art to which the invention appertains, that the same may be incorporated in several different constructions. The accompanying drawing, therefore, is submitted merely as showing the preferred exemplification of the invention.

Referring in detail to the drawing, 10 shows a fabric covered ring embodying the invention. The same may include a split wire ring 11 providing a core around which is wound a decorative thread, or the like, to provide a ring 11a as shown in Fig. 4. Preferably there is an inner winding or covering 12 forming a soft cushioning or filling base for the outer decorative winding or thread 13. As shown in Fig. 4, portions 14 of the ring at opposite sides of the split 14a are flattened and are received in a tubular element 15 longitudinally split at 15a. The same is clamped tightly around the ring portions 14 over the fabric covering 13, which extends right up to the ends of the ring at its split. The tubular element 15 may be so tightly engaged with the ring as to compress the fabric covering 13 to a substantial degree, and since the wall of the element 15 is quite thin, a neat and pleasing effect results. If desired, the tubular element 15 may also be crimped or pinched at 16 to indent the metal for increasing the tightness of its engagement with the ring member 11a.

The ring 10 thus provided is amply reinforced at its split 14a by the tubular element 15 which may be made of a suitable steel or other strong metal for this purpose, and which is capable of holding the portions 14 in true alignment with each other, since the fabric covering forms a cushion that expansively acts between the wire 11 and the tubular reinforcement. Hence any stresses tending to open up the ring at the split 14a are substantially counteracted by the tubular reinforcement and thus an important difficulty heretofore encountered is overcome.

Another advantage inherent in the structure

of the device 10 is that the tubular element 15 serves as an anchorage for the thread wound around the wire core 11 to prevent unraveling thereof, without requiring any special manipulation to secure the thread.

Finally, the tubular reenforcement 15 leaves the fabric covering uncut and free of any mutilation, and may serve as a feature of ornamentation for the device 10.

My fabric covered ring may be used for umbrella straps, and as an eye for buttons or hooks or even as an ornamental feature of dresses, in which case a series of rings may be attached to a dress according to a particular design. Other uses in different fields will also be apparent to those skilled in the art.

The advantages of the fabric covered ring will be further apparent by considering my method for its manufacture. The threads 12, 13 are successively wound around a straight piece of wire to form fabric coverings, and then the wire is cut into sections each of which is shaped to the form shown in Fig. 4. A strip of metal is then cut into sections from which the tubular elements 15 are made. A strip of metal 17 is placed upon a die 18 having a recess or channel 19 of curved or other suitable shape. Then the ring member 11a is applied, so that the portions 14 thereof lie on top of the strip 17, above the concavity 19, and with the split 14a being central of the strip 17. Then a head 20 having at its bottom a centering concavity 21 moves powerfully downward to press the ring portions 14 to deform the strip 17 into the channel 19. Thus the strip 17 is bent into U-shaped form as shown at 17a in Fig. 6. To permit free downward movement of the ring member 11a, the die 18 may be made sufficiently small at one side of the

channel 19 to enter the ring member. Finally, a pair of opposed die members 22 come into action to engage the arms of the element 17a and to press the same tightly around the ring portions

14 to thus complete the tubular element 15. This last operation is accomplished without requiring any movement of the member 19 relative to the die 18. The yielding action of the covering 13 permits a very tight clamping of the tubular element.

In Fig. 7 is shown a modification according to which the tubular element 15 may be constructed with an ornamental projection at a side thereof opposite to the split 14a. Accordingly, I may employ a strip member 23 like that shown at 17 and 17a, but having a projection 24 pressed therein or soldered thereto. For such a structure, the die 25 may have its channel 26 formed with a recess 27 to receive the projection 24 without causing distortion thereof when the strip is forced into the die by pressure on the ring portions 14. In other respects, the structure and operation may be the same as above described.

It will now be seen that I have provided a device and method which fulfill the objects of the invention and are well adapted for practical use.

I claim:

The herein described ring having a core of relatively stiff material forming a split ring having straight aligned portions at the split and being covered by a thread wound around the core, and a longitudinally split tubular reenforcing element receiving said straight aligned portions and bridging the split in said ring core and being clamped on the thread covering of said straight portions, with the thread covering being compressed by the tubular element.

EMIL GRIMALDI.
